DESIGN FOR A TIRE

Charles Samson, Douglaston, N. Y., assignor to
United States Rubber Products, Inc., New York,
N. Y., a corporation of Delaware

Application June 26, 1935, Serial No. 57,410

Term of patent 7 years

To all whom it may concern:

Be it known that I, Charles Samson, a citizen of the United States of America, residing at Douglaston, Long Island, county of Queens, State of New York, have invented a new, original, and ornamental Design for Tires, of which the following is a specification, reference being had to the accompanying drawing, forming part thereof, wherein:—

Fig. 1 is a plan view of a portion of a tire embodying my invention;

Fig. 2 is a side view thereof; and
Fig. 3 is a cross-sectional view of the tire taken along the section line III—III of Fig. 1.

I claim:

The ornamental design for a tire as shown.

Signed at New York, county of New York, and State of New York, this 24th day of June 1935.

CHARLES SAMSON.
